UNITED STATES PATENT OFFICE

JOB HUTCHINSON, OF GREAT NECK, NEW YORK

FUEL RECTIFIER

Application filed October 27, 1925. Serial No. 65,073.

This invention relates to a device for the treatment of fuel for use in internal combustion engines, and more particularly to means adapted to utilize and completely vaporize all portions of the liquid fuel mixed with the air and passed on to the cylinders of the engine.

It is also in the nature of a modification and improvement on the devices of my co-pending applications, Serial No. 679,481, filed December 8, 1923 and Serial No. 16,232, filed March 17, 1925 which has since matured into Patent No. 1,624,249 dated April 12, 1927, in which I disclosed respectively a combined pump, carburetor and vaporizer constituted as a unit and adapted to be attached to the intake manifold of an engine, and a control in which the combined pump, carburetor and vaporizer were embodied with controlling valves in a single unit adapted for direct attachment between an internal combustion engine and a fuel tank. In the present application, which has been termed a fuel rectifier, the principal object is to increase the efficiency and economy of operation by preventing any heavy particles of unvaporized fuel from reaching the cylinders of the engine, whereby carbon deposits would be formed, and also to prevent any of the said heavy particles from passing on through the engine into the crank case and thereby causing serious dilution of the lubricating fluid.

The gasoline fuel in use at this time contains a considerable amount of what are termed heavy ends, which do not vaporize in the temperature prevailing in the carburetor, and therefore, they are carried along in liquid form through the manifold and into the cylinders.

My device comprises a carburetor, a separator of an improved type, and a vaporizer heated by the exhaust gas. In the carburetor, there are no idling features outside the primary venturi which is restricted to a point where the low air velocity will pick up sufficient fuel to run smoothly, so that all fuel, at either high or low speed, will pass through the separator.

To assist in vaporization an electrically heated by-pass is provided, so that a cold

motor may be started in severely cold weather, the mixture from this by-pass also being sent through the separator before it reaches the motor.

A tubular receptacle is also provided under the separator, with a capacity sufficient for collecting the unvaporized fuel prior to the time when the exhaust gas has raised the temperature of the liquid fuel in the receiver, after which the vapor will pass off as fast as the liquid falls into the receiver. The outlet for this vapor has a greater area than the drainage inlet, whereby a circulation is created, as both are subject to the same suction of the air passage in the separator. 55

To prevent overheating the charge, which would result in a lowering of the motor efficiency due to expansion, cold air is taken in direct, and in order to assist the cold air in the breaking up of the fuel in the spray nozzle, the fuel is heated by exhausting the hot gas from the vaporizer through the fuel float chamber. 60

I also show herein a modification, in which a larger vaporizer is used, whereby the known practice of using warm air in the carburetor and keeping the fuel float chamber cool may be availed of. 70

It should be noted that the passage in the separator is circular in form, curved to prevent any harshness or eddy currents, and is also provided with small fins or abutments which serve to collect any heavy particles of fuel without creating any eddy currents or harshness. 80

If desired, this separator could be included as a part of the manifold, but this construction would be more expensive to build and more difficult to connect with the vaporizer, which in itself, would not be a complete device, in view of the fact that various motors have their own type of manifold. 85

My device can be adapted to any manifold by the simple changing of the outlet flange. Other objects and advantages are set forth in the following specification and shown in the drawings, in which: 95

Fig. 1 is an elevation partly in section.

Fig. 2 is a sectional view on the line 2—2 of Fig. 1. 100

Fig. 3 is an enlarged longitudinal sectional view of the nozzle.

Fig. 4 is a view partly in section, showing a modification in which warm air is delivered 5 to the nozzle.

Fig. 5 is a partial transverse sectional view taken on line 5—5 of Figure 4.

In Fig. 1 of the drawings herewith, the numeral 10 indicates the fuel float chamber, 10 11 the vaporizer chamber, 12 the separator chamber, 13 the carburetor, and 14 indicates the electric heating chamber.

The fuel chamber 10 is provided with a fuel inlet connection 15 having an orifice 16 which 15 is controlled by the needle valve 18 operated by the float 21 mounted on the fulcrum 20.

The level of the fuel with relation to the nozzle 34 of the carburetor may be regulated by the addition or removal of the shims 17 20 whereby the proper adjustment of the needle valve 18 may be obtained.

Air is admitted to the chamber 10 through the inlet 19 and the fuel passes to the nozzle 34 through the outlet 22. The lower enlarged 25 end 36 of the nozzle is the low speed or idling nozzle which extends into the restricted portion of the primary venturi 30 rigidly mounted in the top wall 27 of the lower air inlet chamber 25.

30 The numeral 23 indicates the outer wall of the carburetor, 24 is the inner wall, 25 is the lower air inlet chamber provided with the inlet 26, the upper air inlet chamber being indicated at 29 and being provided with the 35 upper air inlet 31.

40 The secondary venturi 32 is mounted in the carburetor so that it may lift as the mixture of air and fuel enters when the throttle valve 54 is partially opened and as the throttle is opened further and the speed of the engine increases additional air is admitted and an increased amount of fuel is drawn from the high speed nozzle 37, which is provided with the port 39, the outer nozzle tube 36 having the port 38.

45 As the secondary venturi 32 moves upwardly, its tapered shape gradually reduces the space around the upper end of the inner nozzle 37, so that the velocity of the air and the supply of the fuel are increased. The 50 upward travel of the secondary venturi 32 is limited by the shoulder 40. The air which enters at the lower inlet 26 and the upper inlet 31 is controlled by the choke valve 70 55 as shown in Fig. 2.

60 The mixture passes on through the valve 54 controlled by the lever 72, into the separator through the entrance 53 to the circular passage 55 which carries on the inner side of its wall the semi-circular baffle projections 57, the high velocity of the mixture causing the heavy unvaporized oil to contact with the wall and said projections and then to 65 flow down into the trough 58 and out through

the drip holes 59 to the collecting receptacle 60 and the heating tubes 61.

As is obvious, when the requisite temperature is reached in the chamber surrounding the tubes 61, the contents will vaporize and 70 ascend to the hot return gas chamber 62, where it is superheated and then passes through the ports 64 to the air stream, following the inner surface of the circular passage 75 free from baffles, to the outlet 65.

The manifold connecting flange is indicated at 65 and through the exhaust connection 66 the hot gas from the exhaust manifold enters and following the course indicated by the arrows passes through the pipe 67 into 80 the vaporizing chamber 11 where it is spread by the baffle 68 and circulates around the cups 61, and then passes on out through the float chamber, exhausting at 69.

To facilitate the starting of the motor in 85 cold weather by pre-heating a mixture drawn from the carburetor through the by-pass 42, an electric heater is provided. This consists of a heating chamber 43, in which a heating coil 48, is mounted on an upper support 49 90 and a lower support 44 insulated by the bushing 45, the binding post being indicated at 46, the electric connection at 74 and the battery at 76, a switch of the usual type being shown at 75. The mixture after being heated passes 95 out through the port 50 which is provided with a plug valve 51 also having a port 52 which registers with the port 50.

In the modifications shown in Figs. 4 and 5, the fuel float chamber 10 is positioned 100 apart from the vaporizing construction, and therefore, the heating tubes 61 therein may be of greater length. In this type the air enters through the intake 78 and is heated in its passage around the hot vaporizing chamber 11 to the inlets 26 and 31 of the carburetor through the connection 79.

105 From the foregoing it will be seen that my device provides an efficient means for increasing the mileage to be obtained in the use of 110 the commercial gasoline now in use, together with a utilization of the heavy ends and incompletely vaporized portions of the mixture developed in a carburetor, which if not treated in this manner would constitute not 115 only a waste but also a menace in the shape of carbon deposits and as a diluent of the lubricant in the crank case.

I claim:—

120 1. A fuel rectifier comprising the combination with a carburetor, of means to separate from a mixture of air and hydro-carbon fuel any incompletely vaporized portions of the mixture, said means consisting of a body having a circular passage connected with the carburetor and provided with semi-circular interior projections, a receptacle for 125 the incompletely vaporized portions of the fuel, and means for raising the region of said receptacle to a high temperature.

2. A fuel rectifier comprising the combination with a carburetor having a fixed primary venturi, a second venturi arranged in tandem and movable with respect to the primary venturi, means to adjust the secondary venturi, a curved chamber into which said venturis discharge, said chamber extending more than a half circle in a level plane and being of circular cross section and baffles in said chamber adapted to separate any incompletely vaporized portions of an explosive mixture of air and hydro-carbon fuel.

3. A fuel rectifier comprising the combination with a carburetor having a fixed primary venturi, a second venturi arranged in tandem and movable with respect to the primary venturi, means to adjust the secondary venturi, a sinuous chamber into which said venturis discharge, said chamber having a circular cross section, a plurality of interior baffles in said chamber, a receptacle below said chamber in open communication at each baffle to receive incompletely vaporized portions of the gaseous fuel by gravity, and means to raise the contents of said receptacle to a high temperature to vaporize said fuel portions, and passages to return the vaporized fuel to said chamber.

4. A fuel rectifier comprising the combination with a carburetor, of means in said carburetor to separate from a fuel mixture passing therethrough any incompletely vaporized portions of the mixture, and a heated by-pass to shunt the throttle, said by-pass being located between the carburetor and said separating means, whereby a rich fuel mixture is provided.

5. In a fuel rectifying device the combination of the following elements; means for pre-heating the fuel in the fuel float chamber; a carburetor; a circular passage connected thereto and provided with semi-circular projections in the interior thereof; a trough in the bottom wall of the said passage, a receptacle adjacent the said trough; a plurality of cups adjacent the said receptacle; and apertures connecting the said receptacle and the said cups.

6. In a fuel rectifying device the combination of the following elements; a carburetor; means adapted to separate from a mixture of air and hydro-carbon fuel any incompletely vaporized portions of the said mixture and comprising a circular passage connected with the carburetor and provided with semicircular projections in the interior thereof, and a receptacle for the said incompletely vaporized portions; and means located between the carburetor and the said separating means and adapted to raise to a high temperature the contents of the said receptacle.

In testimony whereof I have hereunto affixed my signature.

JOB HUTCHINSON.
